Primary Examiner — Susan Bennett Hattan*Assistant Examiner* — Brett Miller(74) Attorney, Agent, or Firm — Mark D. Miller; William K. Nelson(57) CLAIM

We claim the ornamental design for a barrel cooker, as shown and described.

DESCRIPTION

FIG. 1 is a front perspective view of a barrel cooker showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines showing such features as hinges, handles and the like are not part of the claimed design.

1 Claim, 6 Drawing Sheets# US D813,589 S
